UNITED STATES PATENT OFFICE

140,104

DESIGN FOR A PICTURE HOLDER

Theodore Solomon, New York, N. Y.

Application October 31, 1944, Serial No. 116,083

Term of patent 14 years

(Cl. D29—20)

To all whom it may concern:

Be it known that I, Theodore Solomon, a citizen of the United States, residing at New York city, in the county of New York and State of New York, have invented a certain, new, original, and ornamental Design for a Picture Holder, of which the following is a full, clear and exact description.

Reference is to be had to the accompanying drawing, forming a part thereof in which Fig. 1 is a front view of a picture holder, showing the new design; Fig. 2 is an end view of the same, looking at the right end of Fig. 1, and Fig. 3 is a top plan view of the picture holder.

I claim:

The ornamental design for a picture holder, substantially as shown.

THEODORE SOLOMON.
